United States Patent Office

Des. 226,195
Patented Jan. 30, 1973

226,195

HEATER

Benjamin C. Baugh, Robert R. Deines, and Floyd O. Gruver, Jr., Wichita, Kans., assignors to The Coleman Company, Inc., Wichita, Kans.

Filed May 17, 1971, Ser. No. 144,369

Term of patent 14 years

Int. Cl. D23—03

U.S. Cl. D23—124

F/G.2.

F/G.1.

FIG. 1 is a perspective view of a heater embodying our new design;

FIG. 2 is a front elevational view of the heater on an enlarged scale;

FIG. 3 is a top plan view thereof;

FIG. 4 is a right side elevational view thereof;

FIG. 5 is a rear elevational view thereof.
The mesh pattern is partially shown on the front of the heater for convenience of illustration.

We claim:

The ornamental design for a heater, as shown and described.
